UNITED STATES PATENT OFFICE.

MARTIN ZAWISTOWSKI AND NICOLAS KOMOW, OF BROOKLYN, NEW YORK, ASSIGNEES
TO UNITED STATES CLOTH CUTTING MACHINE COMPANY, OF NEW YORK, N. Y., A
CORPORATION OF NEW YORK.

PRESSER-FOOT MECHANISM.

1,287,563.

Specification of Letters Patent. Patented Dec. 10, 1918.

Application filed February 14, 1918. Serial No. 217,212.

To all whom it may concern:

Be it known that we, MARTIN ZAWISTOWSKI, and NICOLAS KOMOW, both citizens of the United States, and both residents of the 5 borough of Brooklyn, in the county of Kings and State of New York, have invented new and useful Presser-Foot Mechanism, of which the following is a specification.

The invention relates to straight-knife 10 cloth-cutting machines, and the object is to provide novel holding and releasing means for the vertically adjustable presser-foot and guard, which shall be especially effective and convenient and well adapted for the 15 type of machine in question. A member is mounted upon the front of the machine turning about a fore and aft axis, and provided with teeth embracing the bar and adapted to hold the same against upward and downward movement, respectively, and this member 20 is turned in one direction by a spring to cause the teeth to engage the opposite sides of the bar, which are grooved for the purpose, and may be turned in the opposite direction to release the bar by a vertically 25 tilting lever fulcrumed upon the side of the machine and connected, as by a forward link, with the double toothed member.

In the drawings:

30 Figure 1 is a side elevation of a machine embodying the invention;
Fig. 2 is a partial front elevation;
Fig. 3 is a rear perspective view of the holding and releasing wheel;

35 Fig. 4 is a vertical section through the holding and releasing means; and

Fig. 5 is a perspective view of the bearing.

Machines of the character indicated are well known and a brief description of their 40 general features will, therefore, be sufficient. The machine has a movable base 1, from which rises a standard support 2 bearing a driving motor 3. This motor drives a straight vertical reciprocating knife 4, suitably mounted upon the front of the machine. A handle 5 projecting rearward from the standard enables the machine to be advanced in the direction of the cut. In the particular machine selected for illustration the 45 front of the motor and the crank and cross-head mechanism (not shown) for driving the knife are inclosed by a front cover 6. The presser-foot 7 is fixed upon the lower

end of a vertical adjustable bar 8, which extends below the front cover 6 in guarding 55 relation to the knife.

Upon the front of the cover 6 is an oblong vertically disposed guide block 9, the body 10 of which may be integral with the said cover. The front of the said body is circularly chambered, the chamber 11 being cut away or open at the sides, owing to the oblong form of the block. It is further provided at top and bottom with slotted openings 12, constituting portions of a vertical 60 passageway, which intersects the chamber 11 and in which the bar 8 is guided. In this preferred construction the four post-like wall portions 13 are tapped for the reception of screws 14, which secure a cover 65 plate 15 to the body 10. A wheel 16 occupies the chamber 11 and is provided with teeth 17 for engaging the grooves 18, which are formed in both sides of the bar 8. The said teeth are preferably constituted by 70 blades 19, which are inserted in inward projecting oblique relation in slots cut in a rim flange 20 of the wheel. This rim flange projects at opposite sides of the lock and is knurled, as indicated, to enable it to be conveniently grasped and turned by hand. Openings 21 cut in the top and bottom of the said rim flange accommodate the guard and presser-foot bar 8. In addition to the 75 journal support which the wheel may receive at its periphery in the arcuate inner surfaces 22 of the posts 13, it is provided with a forwardly projecting shaft portion 23, which finds a bearing in a journal boss 24 on the cover plate 15 in rear of the bearing opening 25. The interior of this boss is enlarged, in order to form a spring barrel 80 which accommodates a spiral spring 26, one end of which is engaged in a hole in the wheel 16 while the opposite end enters a hole 95 in the front of the boss. The blades 19, it will be observed, are located at different heights, the upper one extending obliquely downward toward its side of the bar 8, while the lower blade extends obliquely 100 upward toward the opposite side. The spring 26 is so tensioned as to urge the wheel in the direction which will carry the upper blade upward and inward and the lower blade downward and inward, thereby 105 causing the edges of both blades to enter the

grooves in the opposite sides of the bar. Under these circumstances the upper downwardly inclined blade holds the bar and presser-foot against upward movement, 5 while the lower upwardly inclined blade holds against downward movement. A slight turning movement of the wheel in the opposite direction withdraws the teeth from the bar, which is accordingly free to move in either direction.

10 The release of the holding wheel is effected by means of a lever 27, the forward portion of which is fulcrumed at 28 upon a transverse pivot pin on the side of the front cover 6. A link 29 is pivoted at 30 upon a stub shaft extension of the front end of the lever 27 and at 31 to the rim 20 of the wheel 16. From the fulcrum pivot 28 the lever extends rearward into convenient relation to the handle 5, where it can be operated by downward pressure to turn the wheel member 16 in the releasing direction.

15 What we claim as new is:

1. In a cloth-cutting machine of the kind described, presser-foot mechanism comprising the combination with a vertical slidable guard and presser-foot bar having grooved sides, of a spring-pressed wheel having teeth embracing the bar and coöperative with said grooved sides to hold against upward and downward movement respectively, and a mounting whereon said wheel may turn.

2. In a cloth-cutting machine of the kind described, the combination with a vertical guard and presser-foot bar mounted slidably in front of the knife, of a holding and releasing member having teeth embracing the bar, a mounting whereon said member is journaled to turn about a fore and aft axis, 35 and a spring urging said member in one direction to cause its teeth to grip the opposite sides of the bar, turning of the member in the opposite direction releasing the bar.

3. In a cloth-cutting machine of the kind described, the combination with a vertical guard and presser-foot bar mounted slidably in front of the knife, of a holding and releasing member having teeth embracing the bar, a mounting whereon said member 45 is journaled to turn about a fore and aft axis, a spring urging said member in one direction to cause its teeth to grip the opposite sides of the bar, turning of the member in the opposite direction releasing the bar, and a releasing lever fulcrumed at one side of the machine standard upon a transverse axis and having its forward end connected with said member.

4. In a cloth-cutting machine of the kind described, the combination with a vertical guard and presser-foot bar mounted slidably in front of the knife, of a suitable mounting and a spring-pressed front holding and releasing member journaled thereon 60 to turn about a fore and aft axis, and a side

releasing lever fulcrumed on a transverse axis.

5. In a cloth-cutting machine of the kind described, the combination with a vertical guard and presser-foot bar mounted slidably in front of the knife, of a suitable mounting and a spring-urged wheel journaled thereon to turn about a fore and aft axis and having a rim flange cut away at top and bottom to accommodate said bar, 70 and internal teeth located at different heights on opposite sides of the bar to grip the same.

6. In a cloth-cutting machine of the kind described, the combination with a vertical guard and presser-foot bar mounted slidably in front of the knife, of a suitable mounting and a spring-urged wheel journaled thereon to turn about a fore and aft axis and having a rim flange cut away at top and bottom to accommodate said bar, 80 and oblique inwardly projecting blades inserted in said flange at different heights at opposite sides of the bar.

7. In a cloth-cutting machine of the kind described, the combination of a bearing block 90 upon the front of the machine having a chamber to receive a wheel and a vertical passageway intersecting said chamber, a guard and presser-foot bar in said passageway, and a spring-urged holding and releasing wheel in said chamber with its periphery projecting at opposite sides of the block.

8. In a cloth-cutting machine of the kind described, the combination of a bearing block 100 upon the front of the machine having a chamber to receive a wheel and a vertical passageway intersecting said chamber, a guard and presser-foot bar in said passageway, and a spring-urged holding and releasing wheel in said chamber having a forward projecting shaft portion journaled in the front wall of said block.

9. In a cloth-cutting machine of the kind described, the combination of a bearing block 110 upon the front of the machine having a chamber to receive a wheel and a vertical passageway intersecting said chamber, a guard and presser-foot bar in said passageway, and a holding and releasing wheel in 115 said chamber, said block having a front cover plate provided with a journal boss, a forward projecting shaft portion on the wheel journaled in said boss, and a coil spring housed in said boss and acting upon 120 the wheel in the direction to cause it to grip the bar.

10. In a cloth-cutting machine of the kind described, the combination with a vertical slidable guard and presser-foot bar, of a 125 suitable mounting and a spring-urged wheel journaled in front of said bar having holding teeth at opposite sides and at different elevations to grip and release the bar.

11. In a cloth-cutting machine of the kind described, the combination with a vertical slidable guard and presser-foot bar, of a holding and releasing member for said bar, 5 a bearing block whereon said member is mounted to turn about a fore and aft axis, a spring urging the member in one direc-
tion, a releasing lever fulcrumed upon one side of the machine on a transverse axis, and a link connecting the forward end of said lever with said member.
